UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed February 25, 1922. Serial No. 539,266.

To all whom it may concern:

Be it known that I, EDWARD S. STIMPSON, a citizen of the United States, residing at Hopedale, in the county of Worcester and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms, whereby the operative condition of the loom is changed when the filling in the shuttle is substantially, though 15 not quite, exhausted.

Various types of feeler mechanism have been suggested for effecting replenishment 20 of filling when that in the shuttle has reached a condition of substantial exhaustion; and of such types of feeler mechanism, 25 that known as the "side swipe," wherein the feeler moves longitudinally of the shuttle, has been found admirably adapted for the delicate operation and sensitiveness required in calling the change only when the filling has reached the desired degree of exhaustion.

The object of the present invention is to 30 provide a feeler mechanism of the "side swipe type," wherein the feeler is supported normally in the position to enter the shuttle at right angles to the lay movement, or the longitudinal axis of the shuttle, to feel for the filling on each detecting beat; and when 35 the filling has reached a condition of substantial exhaustion, an auxiliary finger is utilized to effect movement of the feeler longitudinally of the shuttle by the forward pressure upon the auxiliary finger.

40 While the feeler mechanism as hereinafter shown and described is peculiarly well adapted for use in connection with bobbins having the weft or filling wound thereon, it may also be advantageously employed by 45 proper adjustment of the auxiliary finger, for use in connection with quills or cop tubes having the filling or weft wound thereon.

In addition to the above features of the 50 present invention, other novel characteristics and combination of parts will be herein-after described and definitely pointed out in the claims.

In the drawings:—

55 Figure 1 is a perspective view of a feeler

mechanism embodying the present invention and showing only so much of the loom parts as are necessary to make clear to those skilled in the art the construction and mode of operation of the feeler mechanism;

60 Fig. 2 is a cross section through the shuttle, showing the feeler entering the side of the shuttle to feel for the filling;

Fig. 3 is a plan view showing the position and relation of parts when a working 65 supply of filling is present in the shuttle on a detecting beat; and

Fig. 4 is a view similar to that of Fig. 3, showing the position of parts when the filling in the shuttle is substantially exhausted 70 on a detecting beat.

As shown in the drawings, the feeler stand 1 is carried by a bracket 2 adjustably secured to a convenient portion of the loom frame, and the stand is adjustable on the bracket 2 75 by means of the bolt 3 which passes through the slot 4 of the feeler stand. The feeler stand is provided with a rocking bearing 5 through which extends the front end portion 6 of the feeler 7. The feeler stand has a rear 80 bearing for the feeler disposed directly behind the front bearing in such position that a vertical plane extending lengthwise along the longitudinal center of the feeler is at right angles to the axis on which the lay 85 swings, and at right angles to the longitudinal axis of the shuttle, so that as the lay beats up on each detecting beat, the feeler will be moved directly forwardly so long as a working supply of filling is present in 90 the shuttle. In the present instance the feeler stand 1 has upstanding portions 8 at its rear, between which is guided the slide 9, through which the feeler 7 extends, and which constitutes the rear bearing for the 95 feeler. The feeler stand has the feeler-setting cam 10 which engages a projection 11 carried by the feeler (Fig. 1) when the feeler moves to its rearward feeling position under the impulse of a spring 12 disposed between 100 the bearing 5 and the bridge 13 to which the feeler is secured, the effect being that as the spring 12 moves the feeler rearwardly to

feeling position, the cam 10 serves to insure that the feeler 7 shall take a position substantially at right angles to the longitudinal axis of the shuttle.

The bridge 13 has side portions 14, as shown, which rest upon ways 15 carried by the feeler stand, and the spring 12 is shown 110

as bearing against the bridge 13 at one end and against the front bearing 5 at its other end, to normally maintain the feeler in its feeling position.

5 The rear bearing or slide 9 is connected to a transmitter 16 which, through a train of mechanism of any usual and well-known type, effects replenishment of filling when the slide 9 is moved laterally or in a direction longitudinally of the shuttle on a detecting beat.

To maintain the slide 9 in its proper position, between the projections 8 of the feeler stand, a cover plate 17 may be employed, and 15 be secured to the stand by suitable securing means such as the screws 18.

The shuttle 19 is of the usual type and has its front wall slotted as at 20 for the entrance of the feeler. The shuttle in the 20 present instance, is shown as carrying a bobbin 21 by the usual bobbin-holding jaws 22, Figs. 1 and 2. It will be understood, of course, that the shuttle as indicated in Fig. 1, is assumed to be in the shuttle-box, which, 25 however, is not shown, and the shuttle-box is as usual, provided with the slot in its front wall to permit the entrance of the feeler into the shuttle. These features, however, are common and well known, and need no 30 further description.

The feeler tip is of novel construction and consists of a piece of flexible material doubled over upon itself with the fold of material extending beyond the end of the 35 feeler, and constituting the engaging surface of the tip, while the end portions of the folded material are secured in the end of the feeler. This is best illustrated in Figs. 1 and 2, wherein the feeler tip is formed of 40 leather, and has the fold portion 23 extended beyond the end of the feeler 7 and the two end portions 24 of the leather inserted in a slot formed transversely of the feeler stand. From this construction the contacting end 45 of the feeler constitutes a smooth and non-injurious surface against which the filling impact is taken during a detecting beat.

The feeler has mounted on it an auxiliary feeling finger which has an engaging surface 50 at one side of the central longitudinal axis of the feeler and its engaging end is adapted to be encountered by a smooth surface carried by the lay when the filling is substantially exhausted, and to ride laterally along 55 such surface in a direction longitudinally of the shuttle to effect a similar movement of the feeler due to the frontward pressure upon the auxiliary finger.

In the present instance the feeler is shown 60 as having a lateral extension 25 in which is mounted a support 26 for supporting the auxiliary finger. As shown, the support 26 is secured to the extension 25 and has a threaded perforation through which extends 65 the threaded stem 27 of the auxiliary finger

so that the finger may be adjusted toward or from the feeler tip, and may be secured in adjusted position as by a set nut 28. The engaging end of the auxiliary finger is formed by a rolling surface 29 conveniently contrived as a collar mounted in the bifurcated end portion 30 of the auxiliary finger, the construction being such that the roller 29 may move along the smooth surface carried by the lay and perforce move the feeler 75 longitudinally of the shuttle when filling is substantially exhausted on a detecting beat.

The side extension 25 on which the auxiliary finger is supported transversely forms a convenient construction, but the essential 80 is that the engaging end of the auxiliary finger shall be to one side of the longitudinal central axis of the feeler, so that the frontward pressure upon the auxiliary finger will effect movement of the feeler in a direction 85 longitudinally of the shuttle.

Accuracy in operation requires that the feeler shall be responsive and sensitive either to the presence or substantial absence of filling in the shuttle. Owing to the fact that 90 the feeler is mounted to enter the shuttle at right angles to the longitudinal axis thereof, it will be moved frontwardly by the frontward pressure of a working supply of filling on a detecting beat without any tendency to move longitudinally of the shuttle. When, however, the filling is substantially exhausted, the feeler will enter further into the shuttle so that the engaging end or roller 29 of the auxiliary finger will engage the 100 smooth surface on the lay, which may conveniently be the shuttle wall and, owing to the lateral position of the engaging end of the finger relative to the longitudinal axis of the feeler, the engaging end of the finger 105 will move along the smooth surface engaged by it and effect movement of the feeler in a direction longitudinally of the shuttle to initiate replenishment of filling through the transmitter as hereinbefore described. 110

What is claimed is:—

1. A feeler mechanism for looms, having a sidewise movable feeler with a filling engaging tip, front and rear guides disposed one directly behind the other so that the feeler is normally maintained in such position that a vertical plane extending lengthwise along its longitudinal centre through the feeling end of the feeler is at right angles to the axis on which the lay swings and to the longitudinal axis of the shuttle, and an auxiliary feeling finger mounted on the feeler forward of the filling engaging tip and having an engaging portion at one side of the said longitudinal central plane of the feeler to be encountered by a smooth surface and be moved laterally thereof when the filling engaging tip does not make restraining contact with the filling. 120

2. In a feeler mechanism for looms, the 130

combination of a feeler supported to enter the shuttle and feel for the filling on a detecting beat, an auxiliary feeling finger rigidly mounted on the feeler and having an engaging end which is laterally off-set to one side of the feeler that frontward pressure against such off-set end will tend to cause movement of the feeler laterally or in a direction longitudinally of the shuttle, and 10 means for effecting replenishment of filling when frontward pressure of a surface against the off-set end of the auxiliary finger effects such lateral movement of the feeler.

3. In a feeler mechanism for looms, the 15 combination of a feeler that is supported to enter the shuttle at substantially a right angle to the longitudinal axis of the shuttle on a detecting beat and feel for the filling and movable laterally when the filling is 20 substantially exhausted, an auxiliary feeling finger mounted on the feeler and having an engaging end comprising a roller at one side of the longitudinal axis of the feeler to be encountered by and move laterally 25 along a smooth surface on the lay when filling is substantially exhausted on a detecting beat.

4. A feeler mechanism for looms having a side slipping feeler with a filling engaging 30 tip and mounted to enter the shuttle at right angles to the longitudinal axis of the shuttle on a detecting beat to feel for the filling, in combination with an auxiliary finger mounted on the feeler and having a roller at one 35 side of the longitudinal axis of the feeler to be encountered by a surface on the lay and be moved laterally thereof due to the frontward pressure to effect side movement of the feeler longitudinally of the shuttle 40 when the filling is substantially exhausted on a detecting beat.

5. A feeler mechanism for looms, comprising, in combination, a feeler that is mounted to enter the shuttle and feel for the filling in a direction at right angles to the longitudinal axis of the shuttle and to move laterally in a direction longitudinally of the shuttle, an untoothed tip for engaging the filling with non-penetrating contact, an 50 auxiliary finger mounted on the feeler and having an engaging tip off-set laterally at one side of the feeler to be encountered by a smooth surface and to be moved along the same due to the frontward pressure against the laterally off-set end of the auxiliary finger to effect movement of the feeler longitudinally of the shuttle when the filling is 55 substantially exhausted on a detecting beat.

6. A feeler mechanism for looms having 60 a side-wise movable feeler provided with a filling engaging tip and mounted to enter

the shuttle and feel for the filling at right angles to the lay movement that frontward pressure of the filling on the feeler may impart no tendency of the feeler to side slip, 65 in combination with an auxiliary feeling finger mounted on the feeler frontward of the filling engaging tip and laterally off-set to one side of the longitudinal central axis of the feeler to be encountered by and be 70 moved laterally upon a smooth surface due to the impact thereof to effect movement of the feeler longitudinally of the shuttle when the filling engaging tip does not make restraining contact with the filling. 75

7. A feeler mechanism for looms having a side-slipping feeler mounted to enter the shuttle at right angles to the lay movement that it may have no tendency to side slip due to frontward pressure of the filling and 80 having a filling engaging tip in combination with a shuttle feeling finger mounted on the feeler frontward of the filling engaging tip and laterally off-set at one side of the longitudinal axis of the feeler to be encountered 85 by and be moved laterally upon the front wall of the shuttle due to the impact thereof to cause movement of the feeler longitudinally of the shuttle when the filling engaging tip does not make restraining contact 90 with the filling.

8. A feeler mechanism for looms having a side-wise movable feeler provided with a filling engaging tip and mounted to enter the shuttle at right angles to the lay movement, in combination with an auxiliary feeling finger mounted on the feeler frontward of the filling engaging tip and extending to one side of the longitudinal central axis of the feeler, and a roller carried by the auxiliary finger to be encountered by and be moved laterally upon a smooth surface due to the impact thereof to effect movement of the feeler longitudinally of the shuttle when the filling engaging tip does not make restraining contact with the filling. 95

9. In a feeler mechanism for looms the combination of a feeler which enters the shuttle on each detecting beat and feels for the filling, an auxiliary feeler finger mounted on the feeler and off-set laterally to one side of the feeler to be engaged by a smooth surface carried by the lay when the filling is substantially exhausted, and by its offset position relative to the feeler to slide along 100 said smooth surface and effect lateral movement of the feeler and replenishment of filling. 110

In testimony whereof, I have signed my name to this specification.

EDWARD S. STIMPSON.
